DISPLAY RACK

George C. Macdonald, Boston, Mass., assignor
to Megowen-Educator Food Company, Cam-
bridge, Mass., a corporation of Massachusetts

Application August 24, 1937, Serial No. 160,631

2 Claims. (Cl. 211—71)

This invention relates to improvements in a display rack for cracker boxes.

It is an object of my invention to provide a display rack that is adjustable to accommodate any desired number of boxes and which will hold the boxes in readily visible inclined positions close to the top of a counter.

It is a further object to provide a simple, inexpensive construction comprising end brackets and rail members and to shape and position the rails in such manner that the boxes will be securely held against displacement by tipping.

Further objects and advantages of my improvements will be more fully apparent from the following description of preferred embodiments thereof as illustrated in the attached drawings.

In the drawings:

Fig. 1 is a fragmentary elevation of a counter showing the display rack and containers mounted thereon.

Fig. 2 is an end view of the counter shown in Fig. 1 and illustrating in dotted lines the position for a second rack below the first one.

Fig. 3 is a plan view of the rack partially shown in section.

Fig. 4 is a vertical section taken on the plane indicated 4—4 in Fig. 3.

Fig. 5 is a detail vertical section taken on the plane indicated 5—5 in Fig. 4.

Fig. 6 is a front elevation of a counter illustrating a modified arrangement of mounting the display rack.

Fig. 7 is an end view partially in vertical section of the arrangement illustrated in Fig. 6.

Fig. 8 is a detail view of the top of the display stand; and

Fig. 9 is a detail horizontal section taken on the plane indicated 9—9 in Fig. 6.

The counter 10 in Figs. 1 and 2 has a front wall

12 and a top wall 14 which extends for a short distance beyond the upper edge of the front wall 12. The display rack illustrated in Figs. 1 to 5 is intended to be mounted on the front or side wall 12 of the counter. The display rack includes end bracket members 16 approximately triangular in form. Each of the brackets 16 has a rear flange 18 provided with openings 20 to receive screws 22 which attach the brackets 16 to the wall 12. The horizontal bottom edge of the bracket 16 is formed with an inturned strengthening flange 24. The angular upper edge of the bracket 16 is formed with an inturned flange 26, the edge of which is rolled over as at 28 to provide a smooth rounded edge.

The brackets 16 are connected and spaced

apart by the horizontal rail members 30 and 32. The members 30 and 32 are made in various lengths so as to space the brackets at the desired distance apart for the mounting of any desired number of containers such as the cracker boxes 34, the tops of which have removable window covers 36. The lower rail 30 is L-shaped in cross-section as shown in Fig. 4 and includes a short flange 38 and a longer flange 40 disposed approximately at right angles. The edges of the flanges 38 and 40 are rolled over as at 42 and 44 to strengthen the member 30 and to provide smooth rounded edges. At its ends the member 30 has inturned flanges 46 and 48 which are secured by removable fastening means 50 to the brackets 16. The rear and upper rail member 32 is similarly formed L-shaped in section having its flanges 52 and 54 approximately equal in width, the edges of which have rolled over lips 56. The ends of the rail 32 are formed with in-turned flanges 58 secured by the removable fastening elements 60 to the end members 16. The flange 40 of the front and lower rail 30 is disposed in the same plane with the flange 52 of the back and upper rail 32 so as to form a support for the bottom of the container 34. The flange 38 of the rail 30 and the flange 54 of the rail 32 are disposed in parallel planes and extend partially up along the sides of the front and back walls of the container 34. These flanges 38 and 54 serve to hold the container 34 against tipping even when a strong pull is applied to the container in removing the cover therefrom. As illustrated, the top 36 of each of the containers is disposed in an inclined plane immediately beneath the edge of the top wall of the counter 14. If desired, however, a second display rack may be positioned beneath the first rack as illustrated by the dotted lines 62 in Fig. 2.

In certain instances, particularly where the counters are made of metal, it is impossible to secure the rack to the wall of the counter. In such case, special adjustable stands may be provided as is illustrated in Figs. 6 to 9. The counter 70 has a front wall 72, a top wall 74 which overhangs the upper edge of the wall 72 and is formed with a U-shaped band 76 leaving a recess 78 beneath the overhanging edge of the top wall of the counter. I have disclosed a stand comprising a foot member 80, the bottom of which is formed with a right angled base 82 which may be attached to the floor by the screws 84. The top portion 86 of the stand is formed at the lower end hollow in section to telescopically receive the foot member 88. In order to hold the upper and

lower parts of the stand in adjustable position a screw 90 having a knurled head 92 is threaded into the member 80 and is received in a slot 94 formed in the member 86. The top of the member 86 is provided with a rubber head 96 which fits within the recess 78 and bears against the overhanging edge of the counter top wall. The lower flange 98 of the U-shaped portion 76 extend adjacent to the stand to hold against tipping and illustrated in Fig. 7. The member 86 is provided with spaced holes 100 adapted to receive the removable fastening elements 102 which serve to secure the display rack in position in the same manner illustrated in Figs. 1 to 5.

15 The display racks illustrated can be made relatively cheaply and be positioned at the most convenient location in a store and to accommodate any desired number of cracker boxes.

I claim:

20 1. A display rack for cracker boxes, comprising a pair of end brackets having substantially triangular body portions provided on one side with flanges engageable with a vertical support to which the brackets are attachable, and a pair 25 of L-shaped rails fixed at their ends to the re-

spective brackets and holding them in spaced parallel relation, one rail being thus connected to the brackets at the lower front corner thereof and the other rail being attached to the body portions of the brackets intermediate the top and bottom thereof and in engagement with said flanges at the backs of the brackets, said rails being so positioned as to engage the bottoms, fronts and backs of the cracker boxes and thus to hold the boxes in forwardly inclined positions and to prevent accidental forward displacement thereof. 10

2. A display rack for cracker boxes, comprising a pair of horizontally spaced vertically disposed standards adjustable in length to fit beneath the edge of a counter at their upper ends and to engage the floor adjacent the counter at their lower ends, triangular brackets fixed to said standards intermediate the ends thereof, and L-shaped rails fixed at their ends to the brackets, said rails being so positioned as to hold the 20 cracker boxes in forwardly inclined positions and to prevent accidental forward displacement of said boxes. 15

GEORGE C. MACDONALD.
